UNITED STATES PATENT OFFICE.

HANS HANSEN, OF KANSAS CITY, MISSOURI.

DRIVING MECHANISM FOR WASHING-MACHINES.

1,400,743.

Specification of Letters Patent. Patented Dec. 20, 1921.

Application filed April 18, 1921. Serial No. 462,288.

To all whom it may concern:

Be it known that I, HANS HANSEN, a citizen of the United States, residing at Kansas City, in the county of Jackson and State 5 of Missouri, have invented certain new and useful Improvements in Driving Mechanisms for Washing-Machines, of which the following is a description, referring to the accompanying drawings.

10 The invention particularly refers to washing machines of the dasher type driven by a rack bar and relates to an improved coordination of elements as employed in the assemblage. These improvements will be 15 more fully explained in the following description of the drawings.

In the drawings, Figure 1 represents a top view of a washing machine showing the preferred power installation in combination 20 with the driving mechanism. Fig. 2 shows a vertical section taken through the portions of the transmission case and tub as disclosed in Fig. 1. Fig. 3 represents a sectional view of the rack bar and dasher gear and elements in combination as disclosed along the line 3—3, Fig. 1. Fig. 4 is a bottom view 25 of the bottom housing for the dasher shaft gear seen in Fig. 3. Fig. 5 is a top view of the bottom housing seen in Fig. 4. Fig. 6 is 30 a top view of the top housing seen in Fig. 3 including a top view of the dasher shaft gear and a cut section of the dasher shaft. Fig. 7 is a bottom view of the housing seen 35 in Fig. 6. Fig. 8 is a bottom view of the hub crank seen in Fig. 2. Fig. 9 is a top view 40 of the lever for shifting the hub crank seen in Fig. 2. Fig. 10 is a side view showing the catch employed in combination with the shifting lever, Figs. 1 and 2. Similar numerals of reference indicate corresponding 45 parts throughout all the figures of the drawings.

Referring to the drawings, 10 represents the tub of the washing machine, 11 is the 45 cover thereof, 12 the hinged door. Mounted on the cover 11 is seen the motor 13* and motor shaft 13. On the shaft 13 within the transmission case 14 is a worm (not shown) which meshes with the worm gear 15 rigid 50 with the vertical shaft 16 mounted in bearings such as 17 within the case 14. Through the lower portion of the shaft 16 is passed a pin 18. The hub crank 19 has a hub portion 20 loosely sleeved on the vertical shaft 55 16 intermediate the bearing 17 and pin 18,

while the outer end of the crank 19 projects downwardly as a pin 21. The barrel of the hub 20 is horizontally grooved as at 22 to receive the lugs 23, 23 of the forked lever 24 pivotally mounted as at 25 on a portion 60 rigid with the case 14. The pivoted hook 26 mounted as at 27 to the side of the case 14, engages the lever 24 in Fig. 2 to hold the hub crank 19 up on the drive shaft 16 away from the pin 18. A rack bar 28 has its inner end 29, including a ball bearing 30, engaged with the pin 21; a washer 31 and a cotter pin 32 through the pin 21 completes the connection.

The dasher 33 of the washing machine is 70 suspended and carried by the square vertical shaft 34, slidably housed through the square hole 35 in the gear 36. The gear 36 has two hubs 37, 38 respectively mounted in the ball bearings 39, 40 arranged within bottom 75 and top gear housing members 41, 42. The bottom housing 41 is provided with the pocket 43 to receive the bearing 39 and a central opening 43* is left to pass the lower portion of the hub 37 as disclosed. The 80 door 12 is recessed at 44 to receive the pocket projection 43 of the housing 41.

The rack bar 28 engages with the teeth 45 of the gear wheel 36 and rests or moves upon the boss 46 provided on the upper surface of the housing 41. A flange 47 arranged on the housing 41 as an arc on the side opposite the boss 46, supports the top housing 42 and the housings 41 and 42 as assembled are bolted to the cover 12 as at 47*. This 90 housing 42 is recessed at 42* to receive the ball bearing 40 and provided with the central opening 48 to pass the hub 38 as disclosed. At the upper end of the dasher shaft 34 is seen a head 49, by means of which 95 the dasher can be raised to the dotted position seen in Fig. 2 when desired. A spring 50 beneath the head 49 is arranged on the shaft 34 to cushion the fall of the dasher parts from the dotted position shown.

An arm portion 51 projects outwardly 100 from the top housing 42 to furnish a bearing 52 for the vertical shaft 53 loosely mounted therein and provided with the head 54 supported upon the bearing 52. The base of the 105 shaft 53 is decreased in diameter at 55 and upon this portion as a bearing, the wheel 56 is rotatably mounted and held in position by the washer 57 and cotter pin 58 through the shaft 53 as disclosed.

110

The parts being arranged as disclosed in Figs. 1, 2 and 3, to operate the washing machine, the motor is started thus rotating the shaft 16. The hook 26 is removed from engagement with the lever 24, whereupon the hub crank 19 drops by gravity on the shaft 16 until a pair of notches 59 in the base of the hub 20 engage the pin 18, then the hub crank 19 will revolve with the shaft 16 and draw the rack bar 28 back and forth upon the boss 46 to oscillate the gear wheel 36 and thus the dasher shaft 34. A slotted opening 14* is provided through the case 14 to pass the rack bar 28 in its travel. The wheel 56 rotates through friction with the rack bar and serves to keep the rack bar in operative engagement with the gear wheel. It will be noted that by simply pressing down on the lever 24, the hub 20 will be raised to disengage from the pin 18 and the hook 26 spring actuated at 26* will engage the lever 24 to maintain this disengagement. A slot 24* through the case 14 passes the handle of the lever 24. The rack bar 28 during this disengagement and as shown in Fig. 2 is slightly tilted on the boss 46 being brought to the horizontal working position when in driving engagement with the pin 18.

When washing machine operations are completed, the head 54 is raised thus raising the wheel 56 to the dotted position 56*, the rack bar 28 is then swung clear of the door 12 to the dotted position 28*, Fig. 1; the door 12 can then be opened to remove the washing.

The advantages and simplicity of operation of the elements of the invention are apparent and modifications in keeping with the scope of the appended claims may be employed.

Having fully described my invention, what I now claim as new and desire to secure by Letters Patent is:

1. A driving mechanism for washing machines including a transmission case, a power driven vertical shaft mounted in bearings therein, a pin through the base of said shaft, a crank having a hub loosely sleeved upon said shaft above said pin; a rack bar pivotally connecting at its inner end to the outer element of said crank, a bearing support as a rest for the outer portion of said rack bar; clutch mechanism embodied with said crank, a lever pivoted to said case engaging said clutch mechanism, a hook on said case engageable with said lever to effect a tilting of the rack bar 60 on said rest when said lever acts to raise

said crank on said shaft for clutch disengagement.

2. In a washing machine, a door, a bottom gear housing supported by said door, a top gear housing supported above said bottom housing, a gear mounted in bearings and arranged intermediate said bottom and top housings, a square dasher shaft slidably mounted through said door and through a square hole through the vertical axis of said gear, a head on said dasher shaft above said gear and a spring intermediate said head and gear; a projection outwardly extending from said top housing member, a bearing therein, a vertical shaft slidably mounted in said bearing, a head on said shaft above said bearing, a wheel rotatably mounted and carried by said shaft, a rack bar intermediate said wheel and gear and slidably supported upon a boss on said base housing.

3. In a washing machine, a door, a bottom gear housing supported by said door, a top gear housing supported above said bottom housing, a gear mounted in bearings and arranged intermediate said bottom and top housings, a square dasher shaft slidably mounted through said door and through a square hole through the vertical axis of said gear, a head on said shaft above said gear and a spring beneath said head; a projection from said top member, a bearing therein, a vertical shaft in said bearing, a head on said shaft above the bearing, a wheel rotatably mounted on the shaft below the bearing; a rack bar engaging with said gear and supported by a boss on the lower housing member, said wheel preserving engagement of said rack bar with said gear member; a crank pivotally engaging said rack bar, a vertical drive shaft housed within the hub of said crank, a case including bearings for said drive shaft, a lever supported by said case and engaging said crank, pivoted movement of said lever on said case to raise said crank on said shaft operating to tilt the rack bar on said boss to a stationary position and clutch mechanisms operable under pivoted movements downwardly of said lever to engage said shaft and crank to bring the rack bar to a horizontal position and permit movement of said rack bar on said boss during drive shaft rotation to oscillate said gear and dasher shaft substantially as specified.

HANS HANSEN.
